INKING MECHANISM FOR INTAGLIO PRINTING MACHINES

Paul Heimlicher, Bern, Switzerland, assignor to Maschinenfabrik Winkler, Fallert & Co., A. G., Bern, Switzerland

Application November 14, 1951, Serial No. 256,209

Claims priority, application Switzerland
November 17, 1950

7 Claims. (Cl. 101—157)

This invention relates to inking mechanisms for intaglio printing machines.

A primary object of the invention is the provision of improved means for closing off the inking mechanism of an intaglio printing machine without interfering with the necessary adjustments of the doctor blade, which adjustments are normally frequently required during the operation of such a machine.

Another object of the invention is the provision of closure means of the character indicated which are designed and arranged in such a manner between the upper edge of the ink trough and the scraping edge of the doctor blade as to effectively serve their intended purpose without participating in the oscillating movement of the doctor blade.

Because of the readily volatile nature of the colour solvents used in intaglio printing, the inking mechanisms must be sealed as completely as possible to reduce the escape of solvent vapours to a minimum. Since the diameter of the printing cylinder can vary between wide limits depending on the format of the paper being printed, the members ensuring closure of the inking mechanism must be capable of being adapted to cylinders of varying size. These members however must be arranged in such a manner as not to interfere with the adjustment of the doctor to varying angles or, more especially, with the necessary manipulation of the doctor for printing purposes. If the printing cylinder is inked by immersion in the ink, then it must be possible also to lower the ink trough without interference by the closure members. In the various manipulations necessary for printing, it is desirable if possible to dispense with removal and re-mounting of the closure members, which is troublesome.

The invention solves this problem by means disposed so as to close the opening between the doctor edge and the upper edge of the ink trough, said means being stationary and disposed on the one hand near the scraping edge of the doctor and on the other hand near the upper edge of the ink container, and not participating in the reciprocating movement of the doctor.

One embodiment of the invention, chosen by way of example, is illustrated in the accompanying drawings, in which:

Figure 1 is a cross section through the whole of the inking mechanism for intaglio printing;

Figure 2 is a longitudinal section through the doctor adjusting mechanism;

Figure 3 is a top plan view of the inking mechanism for intaglio printing;

Figure 4 is an enlarged sectional detail of the inking mechanism; and

Figure 5 is an alternative form of the mechanism illustrated in Figure 4.

The inking mechanism is provided with a printing cylinder 1 against which the doctor 2 bears. The doctor is anchored between holders 3 screwed to the doctor beam 5. This beam is supported at both ends by bearing

2

members 6 attached to the shaft 7. On one of the bearing members 6 is disposed a worm wheel, in which engages a worm 10, provided with a handle 4, such that by turning the handle 4 and the worm it is possible to rock the doctor beam in such a manner that the doctor edge bears against the printing cylinder 1 and scrapes off the ink on the smooth parts of the printing cylinder. To one end of the shaft 7 is attached crank gear 8 for producing a reciprocating movement of the doctor, while at the other end is attached a lever 9 which is connected to the shaft 7 through a worm 10, a worm wheel 11, bolts 12 and lever 13. The crank gear 8 is driven by an eccentric, not shown in the drawing.

Under the doctor 2 is anchored a cover plate 14 which is bent along the whole of its length at a slight distance from the doctor edge and partly encloses a ledge 15. The ledge 15 is supported by a holder 15a. The length of ledge 15 corresponds to the distance between the side walls 17 of the ink trough, which may be attached to the side walls 18 of the machine or may be made integral with them. The ledge 15 can therefore move only in transverse direction to its longitudinal axis along walls 17 of the ink trough but cannot participate in the reciprocating movement of the doctor 2. Rather the holder 15a slides with the guide 16 in holder 15a, which latter is secured to ledge 15. The ledge 15 is provided at its lower edge with a drainage edge 19 and is pivotally secured to a bifurcated rail 20 behind this drainage edge. A rail 21 is disposed so as to be capable of sliding between the bifurcations of the rail 20 and is at the same time pivotally attached to a lug 22 of a carrier 23. In addition to the ledge 15, the rails 20 and 21 and the carrier 23 and its lug 22, also, are fitted between the slide walls 17 of the ink trough in such a manner as to be capable of sliding along these walls transverse to their longitudinal direction.

To projecting parts 29 of the lug 22 are attached pivots 32 carrying at least one rail 30 capable of sliding along the side walls 17 of the ink trough. A catch 31 prevents the rail 30 from swinging downwards. The catch 31 however can be so placed as to allow the rail 30 to be swung down for cleaning purposes. The projecting parts 29 and pivots 32 do not extend over the entire length of rail 30, thereby providing openings (not shown in the drawing) so that ink scraped off by the doctor can flow between rails 20 and 30 back into the ink trough.

The alternative embodiment illustrated in Figure 5 is provided with a cover plate 33 anchored under the doctor 2 and partly enclosing a lug 34 attached to a rail 35. The rail 35 is pivotally and longitudinally displaceably supported against a carrier 36 rigid with the doctor beam 5. Furthermore, near its drainage edge 37 the rail 35 is pivotally but not longitudinally, i. e. axially, displaceably held by a rail 38 which itself is pivotally but not longitudinally displaceably attached to the lug 22. The rails 35 and 38 do not participate in the oscillating movement of the doctor 2 and are fitted so as to be capable of sliding between the side walls 17 of the ink trough.

The carrier 36 is at one end rotatably mounted on a bushing 24 and at the other end is rigidly connected to a hub 25 of the lever 9, which hub is rotatably mounted in the wall 18. The lever 9 is provided with a stud 26 which engages in notches 27 supported by the wall 18 when the lever 9 is in certain positions. When the doctor 2 is in operative position the lever 9 is always in the same position. By means of the worm 10, the bolts 12 can be moved forwards or backwards, depending on the diameter of the printing cylinder, the shaft 7 and the doctor 2 participating in this movement because of the positive connections. The angle 28, between the doctor 2 and the tangent to the circumference of the cylinder 1 at the

point where the doctor is in contact with it, can be adjusted, by means of the worm 10, to the proper size as determined empirically. If the doctor has been adjusted for a certain cylinder diameter and is now to be removed, this is effected by pulling the stud 26 out of the notch 27 and swinging the lever 9 rearwards. If it is desired to return the apparatus to the operative position, the lever 9 is swung back until it reaches the notch 27. Both the doctor and also the covering means are now back in their former position. The two rails 20 and 21, capable of sliding relatively to one another, slide towards or away from one another when the doctor angle 28 is being altered and when the doctor is being adjusted to a different cylinder diameter. In the alternative embodiment illustrated in Figure 5, the rail 38 swings slightly upwards or downwards. Covering on the side remote from the doctor is effected by means of a cover 39 known in itself (Figure 1).

What I claim is:

1. In an inking mechanism for intaglio printing machines having an ink trough, a printing cylinder, a reciprocable doctor blade having a scraping edge and adapted for cooperative engagement with said cylinder, and a doctor shaft supporting said doctor blade; the combination of a carrier element arranged for movement relative to said doctor shaft, closure means interposed between said scraping edge and the upper edge of said ink trough, said closure means being supported independently of said doctor blade and being arranged for closing off the area between said doctor blade and the upper edge of said ink trough without interfering with the reciprocation of said doctor blade along said cylinder, said closure means comprising a pair of telescopically slideable members, the lower end of one of said members being pivotally attached to said carrier element, the other of said members being bifurcated for slidably retaining said first mentioned member and being pivotally attached to said inking mechanism adjacent the scraping edge of said doctor blade.

2. An inking mechanism in accordance with claim 1, including a further carrier element rigidly secured to said doctor shaft adjacent the scraping edge of said doctor blade, said further carrier element pivotally carrying said bifurcated member.

3. An inking mechanism in accordance with claim 2, including a cover plate secured to said doctor blade adjacent said further carrier element, said cover plate being

provided with a hollow wedge-shaped portion partially enclosing a correspondingly shaped projecting portion of said further carrier element.

5. In an inking mechanism for intaglio printing machines having an ink trough, a printing cylinder, a reciprocable doctor blade having a scraping edge and adapted for cooperative engagement with said cylinder, and a doctor shaft supporting said doctor blade; the combination of a first carrier element arranged for movement relative to said doctor shaft, closure means interposed between said scraping edge and the upper edge of said ink trough, said closure means being supported on said carrier element independently of said doctor blade and being arranged for closing off the area between said doctor blade and the upper edge of said ink trough without interfering with the reciprocation of said doctor blade along said cylinder, said closure means being pivotally attached to said carrier element, and a second carrier element rigidly secured to said doctor shaft adjacent the scraping edge of said doctor blade, the upper end of said closure means being pivotally attached to said second carrier.

20 6. An inking mechanism in accordance with claim 4, wherein said first carrier element is disposed concentrically with respect to said doctor shaft.

25 7. An inking mechanism in accordance with claim 5, wherein said closure means comprises a primary member and a secondary member pivotally attached at one end to the latter, the opposite end of said secondary member being pivotally attached to said first carrier element.

30 8. An inking mechanism in accordance with claim 4, including a bolt disposed exteriorly of said trough, a lever connecting said bolt and said doctor shaft, and gear means operatively connected to said bolt for turning same and pivoting said lever and said shaft, whereby the angularity 35 of said doctor blade may be varied.
